UNITED STATES PATENT OFFICE.

FRANK JANOUCH, OF LINCOLN, NEBRASKA.

CORK-EXTRACTOR.

1,110,265.

Specification of Letters Patent. Patented Sept. 8, 1914.

Application filed June 17, 1913. Serial No. 774,183.

To all whom it may concern:

Be it known that I, FRANK JANOUCH, a citizen of the United States, residing at Lincoln, in the county of Lancaster and State of Nebraska, have invented new and useful Improvements in Cork-Extractors, of which the following is a specification.

This invention has relation to cork extractors and it consists in the novel features 10 hereinafter described and claimed.

An object of the invention is to provide a cork extractor of simple structure which may be conveniently carried in the pocket, the said extractor being provided with 15 points adapted to straddle a cork whereby the cork may be readily withdrawn from the mouth of a bottle. The points are adapted to slide within the casing of the extractor when not in use and consequently the 20 device may be carried in the pocket of a garment without having the points exposed to the material of the garment.

In the accompanying drawings Figure 1 is a perspective view of the extractor showing the points extended with relation to the casing. Fig. 2 is a side elevation of the same with part of the casing removed. Fig. 3 is a transverse sectional view of the same.

The extractor comprises a casing 1 which is made up of two sections secured together by means of transversely disposed screws 2 and 3. A single screw 3 is located in the vicinity of one end of the casing while a pair 35 of screws 2 are located in the vicinity of the opposite end. The screws 2 are spaced from each other. U-shaped members 3' are slidably mounted in the casing 1 and their inner side portions lie between the screws of the 40 pair of screws and the said side portions of the said members are provided with heads 4 which are adapted to encounter the screws 2 when the U-shaped members 3' are moved in one direction with relation to the casing 45 and are adapted to encounter the single screw 3 when the members 3' are moved in an opposite direction in the casing. Thus the movement of the members 3' within the casing is limited. The outer side portions 50 of the members 3' fit snugly against the inner sides of the casing and carry flexible points 5 which points are tapered longitudi-

nally. The outer ends of the points 5 are disposed outwardly as at 6.

When it is desired to carry the extractor 55 in a pocket or when it is not in use, the U-shaped members 3' may be moved longitudinally of the casing 1 so that the heads 4 will encounter the screws 2. At this time, the points 5 are located within the casing 1. 60 When it is desired to use the extractor, one of the members 3' is moved longitudinally in the casing until its attached head 4 comes in contact with the single screw 3. This projects the point 5 beyond the end of the 65 casing and this point is then inserted between the cork and neck of a bottle and passed down the whole or any part of the length of the cork. After this has been done the other member 3' is moved and its 70 point 5 inserted in the same manner so that the cork is received between the said points. By reason of the fact that the extremities of the points 5 are outwardly disposed the said points will not have a tendency to tear the 75 cork as they are being inserted between the inner surface of the mouth of the bottle and the outer sides of the cork. By working the cork and simultaneously pulling the same it may be readily extracted from the 80 mouth of the bottle.

Having described the invention what is claimed is:

1. A cork extractor comprising a casing consisting of side portions, securing devices 85 connecting the side portions together, members movably mounted in the casing and limited in their movements by the said securing devices, and points carried by the said members. 90

2. A cork extractor, comprising a casing consisting of side members, securing devices connecting said side members together, U-shaped members slidably mounted in the casing and having heads in the path of 95 movement of which the said securing devices are located, and points carried by the said U-shaped members.

In testimony whereof I affix my signature in presence of two witnesses.

FRANK JANOUCH. [L. S.]
